GEORGES GASCARD, OF PARIS, FRANCE.

MACHINE FOR WAXING SHEETS OF CIGARETTE-PAPER.

1,315,925.

Specification of Letters Patent. Patented Sept. 9, 1919.

Application filed March 27, 1918. Serial No. 225,093.

To all whom it may concern:

Be it known that I, GEORGES GASCARD, of 3 Rue Saulnier, Paris, France, manufacturer, have invented Machines for Waxing 5 Sheets of Cigarette-Paper, of which the following is a full, clear, and exact description.

The various types of machines heretofore known for waxing sheets of cigarette paper have only a very small output and do not 10 always assure work which is entirely satisfactory especially in the event of the paper being of inferior quality or imperfectly calendered.

The subject of this invention is an improved machine which by reason of its special construction offers the advantage of assuring a large output and, moreover, a perfectly regular and even application of the paraffin wax whatever may be the quality 20 of the paper even when the latter is not well calendered.

The improved machine is essentially characterized by the combination:

(a) of a cylinder furnished with a blanket 25 of woolen fabric, cardboard or other flexible soft material intended to convey the sheet to be waxed and to afford a soft or yielding supporting surface for the latter while it is submitted to the action of waxing 30 rollers.

(b) of waxing rollers rotating at a peripheral velocity which is greater than that of the said cylinder.

By reason of this combination the waxing 35 rollers exercise friction on the sheet of paper and since the surface supporting this sheet is of a soft or yielding character this friction is applied in a uniform manner over all the parts to be waxed so that under these 40 conditions the waxing is always effected in a very rapid and perfectly regular manner whatever may be the quality of the paper.

This improved machine is also characterized by a special manner in which the cylinder 45 conveying the sheet to be waxed is mounted, which permits this cylinder to be removed out of contact with the waxing rollers when there is no sheet of paper under treatment in the machine.

50 The accompanying drawing shows by way of example one constructional form of the improved machine, in which—

Figure 1 is a front view and

Fig. 2 a side view thereof.

55 Fig. 3 shows a transverse section drawn

to an enlarged scale, taken on the line 3—3, Fig. 1.

As shown in this drawing, the machine comprises a frame *a* carrying at its ends two guideways *b*, *b'* in which are situated sliders *c*, *c'* forming shaft bearings; in these latter the ends of a shaft *d* can rotate freely, and this shaft carries a cylinder *e* furnished with a blanket *f* of woolen or other soft material.

60 The sliders *c*, *c'* rest respectively on two eccentrics *g*, *g'* keyed on two shafts *h*, *h'* carried on the guideways *b*, *b'*; these two shafts are connected together by a rod *i* pivotally connected at its two ends to two arms *j*, *j'*, 70 respectively keyed on the two shafts *h*, *h'*. An operating lever *k* movable about a pivot pin *l* carried on the frame, is connected by a rod *m* to the pivotal connection of one of these arms *j* with the rod *i* in such a manner 75 that by moving this lever *k* a simultaneous angular displacement is communicated to both eccentrics *g*, *g'* whereby a rising or falling movement is communicated to the sliders *c*, *c'* and consequently to the cylinder *e*, as hereinafter mentioned.

80 Above the cylinder *e* is arranged an inclined feed table *n* on which are placed the sheets to be waxed, before they are fed to the machine.

85 A series of endless cords *o* passing around suitably placed idle pulleys *p* retain the sheet of paper in contact with the exterior surface of the blanket *f* carried by the cylinder *e*, during the working period.

90 The cylinder *e* receives its rotary movement from a transmission shaft *q* carried by the frame of the machine, through a belt *r* passing around pulleys *s*, *t* respectively keyed on the shafts *q* and *d*.

95 Below the cylinder *e* the frame carries a hollow shaft *u* rotating freely in bearings *v*, *v'* fixed on the guideways *b*, *b'* and carrying rollers *w* suitably spaced apart; this hollow shaft receives its motion of rotation 100 from the transmission shaft *q* through a belt *x* and pulleys *y*, *z* keyed respectively on this shaft *q* and on the shaft *u*; the diameters of the pulleys are determined so that the peripheral velocity of the rollers *w* is greater 105 than that of the blanket *f* carried by the cylinder *e*. The hollow shaft *u* is heated internally by a circulation of warm air, water, steam or other fluid.

110 The wax is deposited on the rollers *w* by

a cylinder 1 furnished with a woolen covering 2 and dipping into a tank 3 containing paraffin wax heated by a row of gas jets 4. This cylinder is driven by the shaft *q* by means of a belt 5 and pulleys 6 and 7.

Opposite the rollers *w* are mounted doctor rollers 8 adjustably mounted on a fixed support which permits the thickness of the layer or coating of wax deposited on each 10 of these rollers *w* to be regulated.

The operation of this machine is as follows:

The sheets of paper to be waxed, placed on the table *u* are pushed forward one by one 15 until they come against the cylinder *e* and are seized between the latter and the cords *o*, an extension of which also assists in conducting the sheets away. Each sheet of paper thus carried along is subjected to the action 20 of the waxing rollers *w*, which are rotated at a peripheral velocity greater than that of the cylinder *e*, as herein above mentioned, and exercise friction on this sheet while at the same time they deposit the wax 25 with which they are coated.

On leaving the machine each waxed sheet is conducted away by a series of cords 10 and placed in a collecting box.

The sheets to be waxed, instead of being fed to the machine by hand, may be introduced mechanically by an automatic apparatus for feeding sheets one by one from a pile, similar to those employed in printing machines.

35 When the feeding of sheets of paper into the machine is stopped, the lever *h* is moved in such a manner that it raises the cylinder *e* and thus contact of the blanket *f* against the waxing rolls *w* is prevented.

40 It is to be understood that the arrangement hereinabove described is given only by way of example and that the form, dimensions and details of construction of the constituent members of this machine can be 45 modified.

What I claim is:

1. A machine for waxing sheets of cigarette paper, comprising in combination, a rotary cylinder, a blanket of yielding material, adapted to convey the sheet to be waxed and provide a yielding supporting surface behind the latter during the waxing operation, and waxing rollers adjustably mounted and rotating with a peripheral velocity greater than that of the said cylinder and exercising friction on the sheet of paper and simultaneously applying the wax.

60 2. A machine for waxing sheets of cigarette paper, comprising in combination, a rotary cylinder, a blanket of yielding material, carried thereon and adapted to convey the sheet to be waxed and to provide a yielding supporting surface behind the latter during the waxing operation, waxing rollers 65 mounted to rotate with a peripheral velocity

greater than that of the said cylinder and exercising friction on the sheet of paper and simultaneously applying wax, and means for separating at will the conveying cylinder from the waxing rollers when the 70 feeding of sheets of paper into the machine is stopped.

3. A machine for waxing sheets of cigarette paper, comprising in combination, a rotary cylinder, a blanket of yielding material surrounding the same, a feed table above said cylinder, idle pulleys, endless cords passing around said idle pulleys and adapted to retain the sheet of paper in contact with the surface of the blanket during the 80 working period, waxing rollers, means for transmitting rotary motion thereto whereby their peripheral speed will be greater than that of the blanket, and means for separating at will the conveying cylinder from the 85 waxing rollers to prevent contact of the cylinder blanket with the waxing rolls when feeding of the sheets of paper into the machine is suspended.

4. A machine for waxing sheets of cigarette paper comprising a rotary cylinder, a blanket of yielding material thereon, a feed table, means for retaining the sheet of paper in contact with the surface of the blanket, waxing rollers, a hollow shaft on 90 which said waxing rollers are mounted, means for circulating a fluid heating medium through the said hollow shaft, means for transmitting to the said shaft a rotary movement whereby the peripheral velocity 100 of the said waxing rollers is greater than that of the blanket on the conveying cylinder, a tank containing paraffin wax, means for heating the said tank, a rotary cylinder having an absorbent covering and mounted 105 to rotate in the contents of said tank and in contact with the waxing rollers, doctor rollers mounted to contact with the waxing rollers, and means for separating at will the conveying cylinder from the waxing rollers. 110

5. A machine for waxing sheets of cigarette papers, comprising a rotary cylinder, a blanket of yielding material surrounding the same, bearings in which the said cylinder rotates, said bearings slidably mounted on 115 the frame of the machine, eccentrics on which said bearings rest, means for actuating the said eccentrics simultaneously to impart a vertical movement to the cylinder, a feed table, means for retaining the sheet of 120 paper in contact with the surface of the blanket, waxing rollers and a hollow shaft on which the said rollers are mounted.

6. A machine for waxing sheets of cigarette paper comprising in combination, a 125 cylinder, a flexible blanket mounted on its periphery, a series of endless cords positioned to retain sheets of paper against the surface of said blanket, waxing rolls adapted to apply wax to said sheets, and a hollow shaft 130

upon which said rolls are mounted, means for circulating a fluid heating medium through said hollow shaft, a conveying cylinder in which said hollow shaft is mounted, means for imparting a rotary movement to the conveying cylinder and waxing rolls, whereby the peripheral velocity of the waxing rolls is greater than the velocity of the conveying cylinder, and means for moving 10 the conveying cylinder out of contact with

the waxing rolls, when feeding of the sheets of paper into the machine is suspended.

The foregoing specification of my "ma-
chine for waxing sheets of cigarette paper" 15
signed by me this twenty-sixth day of Febru-
ary, 1918.

GEORGES GASCARD.
